UNITED STATES PATENT OFFICE

ALBERT A. CRIPPS, OF DETROIT, MICHIGAN, ASSIGNOR, BY MESNE ASSIGNMENTS, TO CHRYSLER CORPORATION, A CORPORATION OF DELAWARE

VEHICLE BODY SILL ASSEMBLY

Application filed July 2, 1933. Serial No. 289,890.

This invention relates generally to vehicle body sill assemblies and consists of certain novel features of construction, combinations and arrangements of parts that will be hereinafter more fully described and particularly pointed out in the appended claims.

In the accompanying drawings:

Figure 1 is a fragmentary side elevation of a motor vehicle having a sill assembly embodying my invention.

Figure 2 is an enlarged top plan view of one of the body sills.

Figure 3 is a side elevation of the body sills shown in Figure 2.

Figure 4 is an enlarged fragmentary vertical sectional view taken on the line 4—4 of Figure 1.

Figure 5 is an enlarged fragmentary vertical sectional view taken on the line 5—5 of Figure 1.

Figure 6 is an enlarged fragmentary vertical sectional view taken on the line 6—6 of Figure 1.

Figure 7 is an enlarged fragmentary vertical sectional view taken on the line 7—7 of Figure 1.

Figure 8 is an enlarged fragmentary side elevation of my sill assembly.

Figure 9 is a fragmentary vertical sectional view taken on the line 9—9 of Figure 8.

Figure 10 is a fragmentary vertical sectional view taken on the line 10—10 of Figure 8.

Figure 11 is a fragmentary horizontal sectional view taken on the line 11—11 of Figure 8.

Figure 12 is an enlarged fragmentary side elevation of another portion of my sill assembly.

Figure 13 is a fragmentary vertical sectional view taken on the line 13—13 of Figure 12.

Figure 14 is a fragmentary sectional view taken on the line 14—14 of Figure 12.

Referring now to the drawings, the reference numeral 1 designates a chassis side sill or frame member. A body sill 2 is carried by the chassis frame member and supports suitable flooring 3 and a covering or mat 4. A cowl or shroud 5 rises from the body sill 2 at the

forward end thereof. A splash board or apron 6 is clamped between the sills 1 and 2 and depends from the latter to the running board 7. Front and rear quarter pillars 8 and 9, respectively, constitute supports or hinge posts for suitable swinging doors 10 and 11, and 12 is an intermediate pillar, constituting a common abutment or jamb for both doors 10 and 11. As shown, the chassis frame member 1 is channel shaped and is arranged on edge with the channel thereof opening inwardly. The body sill member 2 is preferably formed of two sections 13 and 14 which are rigidly secured together in overlapping relation at a point between the pillars 9 and 12 and are curved longitudinally to conform to the longitudinal curvature of the vehicle body. In advance of the front pillar 8 the forward section 13 of the body sill comprises an inverted channel 15 that opens downwardly and straddles the upper edge of the chassis sill 1. For a portion of its length, preferably adjacent to the pillar 8, the outer wall 16 of the channel 15 is provided at its lower edge with a lateral flange 17 that projects outwardly therefrom and constitutes an attaching flange for the cowl 5. From the front pillar 8 to the joint between the sections 13 and 14, the forward section 13 of the body sill preferably comprises in cross section two

reverse channels 18 and 18' with the common web 19 thereof upon the outer side of and secured by bolts 20 to the vertical web 21 of the chassis sill 1. The inner channel 18 constitutes a rearward extension of the channel 15 and straddles the upper edge of the chassis frame member or sill 1, while the outer channel 18' opens upwardly toward the flooring 3 and receives and conceals the heads of the securing bolts 20. Preferably, the outer wall 22 of the channel 18' extends upwardly at one side of and terminates substantially flush with the upper surface of the mat or floor covering 4 and constitutes an abutment for

suitable weatherstrips 23 and 24 extending transversely of the doors 10 and 11 respectively below the interior trimming material 25 and 26 thereof. The rear section 14 of the body sill is inverted L shape in cross section and overlaps and is riveted to the inner chan-

nel 18 of the forward section 13. In rear of the forward section 18, the horizontal portion 27 of the rear section rests upon the upper edge of the chassis frame member 1, while the depending portion 28 of said rear section is upon the outer side of the web 21 of the chassis frame member and constitutes an attaching flange for the inwardly depressed wheel housing panel 29. Preferably, the outer wall 22 of the outer channel 18' is provided at its forward end with an inward depressed or embossed portion 30, to which a lateral flange 31 of the front pillar 8 is secured, and is provided adjacent to the forward end of the rear section 14 with a recess 32 for the reception of the intermediate pillar 12. As shown in Figure 14, the outer face of the pillar, attaching flange 31 is substantially flush with the outer face of the wall 22, and as shown in Figures 9, 10 and 11, the lower end of the intermediate pillar 12 rests in the recess 32. This pillar 12 is preferably channel shaped with the channel thereof opening inwardly and has lateral attaching flanges 33 and 34 disposed upon and secured to the inner side of the outer wall 22 of the outer channel of the body sill. The rear quarter pillar 9 is preferably mounted on a wheel housing bracket 35 which projects upwardly from and is rigidly secured to the rear section 14 of the body sill.

Thus, from the foregoing description, it will be readily apparent that I have provided an exceptionally strong and durable sill structure, which, due to its construction, enables lighter gauge sheet metal to be used in the manufacture thereof, and which is designed in such a way that the sections 13 and 14 thereof may be readily formed and assembled and the body panels and parts such as the shroud or cowl 5, rear quarter panel or wheel housing 19 and pillars 8 and 12 may be secured directly thereto, thereby obviating the use of extra or supplemental attaching brackets. The outer channel 18' of the body sill conceals the body sill securing elements, such as the members 20 and 20', so that a neat appearance is provided, and this outer channel may be either of constant or variable width throughout its length, as may be found desirable. In addition, the provision of the depressed portion 30 and of the recess 32 in the body sill serves to position the pillars 8 and 12 with respect to the sill and thereby facilitates and insures accuracy of assembly.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:—

1. In a sill assembly, the combination with

a chassis sill, of a body sill carried thereby and including a section having inverted channels extending longitudinally thereof, a flange of one of said channels extending upwardly with a free edge constituting a door weather strip abutment, and a connection between said sills including an element received in and concealed by one of the channels aforesaid, said connection extending horizontally through said sills.

2. In a sill assembly, the combination with a chassis sill, of a body sill carried thereby and including a section having inverted channels extending longitudinally thereof, one of said channels straddling a portion of said chassis sill and a wall of the other of said channels extending upwardly with the free edge constituting a door weatherstrip abutment.

3. A sill having two oppositely opening longitudinally extending channel shaped portions, an outer wall of one of said channel shaped portions extending upwardly with a free edge constituting a door weather strip abutment.

4. A body sill formed of two sections having portions secured together in overlapping relation, one of said sections having oppositely opening channel shaped portions provided with a common intermediate web and an upwardly extending rear flange, a chassis sill, and fastening means extending through said web of said chassis sill.

5. In a sill assembly, the combination with a chassis sill having a vertical web and a lateral flange, of a body sill having a portion on said lateral flange and a depending portion upon the outer side of and secured to said web, a flange on said body sill free at its outer edge providing one of said portions being provided with means for concealing the securing means and constituting a door abutment.

In testimony whereof I affix my signature.

ALBERT A. CRIPPS.
